[57] ABSTRACT

A manufacturing process and apparatus for making surgeon' gloves utilizing a plurality of pallets, each pallet with a plurality of glove forms thereon, moving sequentially through a plurality of stations which form a closed loop. The pallets and glove forms are removably mounted to facilitate substitution of other pallets with other sizes of forms.

GLOVE MANUFACTURING

BACKGROUND OF THE INVENTION

This invention relates to the manufacture of dipped rubber goods and more particularly to a new and improved method and apparatus for economically manufacturing latex rubber surgeons' gloves.

Heretofore in the manufacture of rubber dipped articles, such as latex rubber surgeons' gloves, considerable hand operations were essential to their manufacture thereby making the unit cost high. Although certain improvements were made in some areas of the handling of the glove forms, the improvements in manufacturing were directed principally to the manual manipulation of a single group of mandrels through several operations. Such action required complex motions with intricate mechanisms and related parts, without materially improving output and cost. Those improvements directed to multiple forms on a single pallet required extensive manual manipulative steps which increased the cost per unit produced.

The purpose of this invention is to provide a new and improved method and apparatus which materially increases the production and quality of latex dipped products while reducing the production costs. Further, the accuracy of reproducibility has been enhanced by this invention. The pallets are automatically manipulated over the full closed path of the manufacturing operation such that the finished glove is lubricated on the inside as well as the outside without requiring an inversion of the glove or requiring a separate operation of dusting the gloves.

BRIEF DESCRIPTION OF THE INVENTION

The present invention is directed to a manufacturing process and apparatus which provides for a plurality of stations (preparation or treatment) cooperative with a latex dip station for making latex gloves. The stations are interconnected automatically such that a plurality of pallets with straps and glove forms thereon are manipulated at the stations and are continually moved automatically and sequentially from one station to the other. Each pallet supports a plurality of removable straps and glove forms to facilitate the changing of sizes.

BRIEF DESCRIPTION OF THE DRAWINGS

FIG. 1a and 1b are schematic side elevational views of the glove manufacturing apparatus, which when longitudinally aligned illustrate the complete closed flow path of the pallets in the installation;

FIG. 2 is an enlarged side elevational view of the forward portion of the glove manufacturing apparatus showing the indexer means for the pallets;

FIG. 3 is an enlarged side elevational view of that portion of the apparatus adjoining the indexer means which manipulates the pallets through the cleaning operations;

FIG. 4 is a plan view of that portion of the apparatus shown in FIG. 3 which adjoins the indexer means for moving the pallets into and out of cleaning and rinsing tanks;

FIG. 5 is a side elevational view of the rearward portion of the glove manufacturing apparatus showing a pallet with glove forms thereon;

FIG. 6 is a rear elevational view of the glove manufacturing apparatus;

FIG. 7 is a side elevational view of a transfer means operating on the upper portion of the glove manufacturing apparatus between two conveyors;

FIG. 8 is an end view of the transfer means shown in FIG. 7;

FIG. 9 is a fragmentary view of a guide rail being supported by a truck and bracket;

FIG. 10 is a cross-sectional view of the guide rail and truck taken on line 10—10 of FIG. 9;

FIG. 11 is a fragmentary enlarged view of an end portion of a pallet as guided by the guide rails and the chain taken along lines 11—11 of FIG. 2;

FIG. 12 is a fragmentary side elevational view of a locking means for the pallet;

FIG. 13 is a fragmentary front elevational view of the locking means shown in FIG. 12;

FIG. 14 is a front elevational view of a transfer means for a transfer means shown in the locked position;

FIG. 15 is a front elevational view of the locking means shown in FIG. 14 in the unlocked position;

FIG. 16 is a plan view of the locking means for the transfer means shown in FIG. 14;

FIG. 17 is a side elevational view of the locking means shown in FIG. 14 in the unlocked position;

FIG. 18 is a side elevational view of the locking means shown in FIG. 15 in the locked position;

FIG. 19 is a fragmentary cross-sectional end view of a portion of a pallet and a strap taken on line 19—19 of FIG. 20;

FIG. 20 is a fragmentary front elevational view of a portion of a pallet and strap;

FIG. 21 is a front elevational view of a pallet and strap with portions broken away, showing the pallet riding in the guide tracks;

FIG. 22 is a side elevational view of one of the pallets, with portions broken away, showing straps and glove form mounted thereon;

FIG. 23 is a cross-sectional view of a latex dip tank;

FIG. 24 is a cross-sectional view of the latex dip tank shown in FIG. 23;

FIG. 25 is a schematic drawing of the controls for the latex dip tank; and

FIG. 26a and 26b in longitudinal alignment is a timing chart of the glove making apparatus.

DETAILED DESCRIPTION

Referring to the drawings, and more particularly to FIG. 22, there is shown a portable articulated pallet 10 which is used to handle, store and manipulate a plurality of glove forms along an apparatus to be described. Each pallet consists of a plurality of elongated tubular channel members 11 arranged in parallel rows with each member having a longitudinal center line. Each tubular channel member 11, see FIG. 19, has a pair of laterally extending projections 12 that extend along the respective upper side edges thereof for the full length of the pallet. A bracket 13 is suitably secured to the respective side ends thereof to facilitate the joining of the elongated tubular members 11 into a single unitary pallet. Each bracket 13 has a pair of bores at the respective ends thereof such that adjacent brackets have portions overlapping with their bores aligned for receiving pivot means 14 consisting of an axle 15 and a

wheel or roller 16 journaled thereon. The pivot means 14 permits the respective channel members 11 to pivot in a direction that would swing the respective tubular channel members about the axles or wheels 16. Each channel member 11 has stop means at the center portion consisting of a plate 17 suitably secured to the upper surface portion thereof to limit the inward movement of a strap 20 to be described and a spring clip 18 (FIG. 21) suitably secured to the lower side surface portion at the center of each channel member 11 for a purpose to be described.

A generally U-shaped strap member 20 with a projection 22 on the outer edge portions of the respective leg members is adapted to receive the projections 12 of the tubular channel member 11, such that the strap members 20 are adapted to abuttingly engage the plate 17 and the clip 18. As shown in FIGS. 21 and 22, there are five channel members 11, with each channel member 11 receiving two straps 20 thereby providing 10 straps per pallet. Each strap member 20 has secured thereto, as by a conventional bolt and nut arrangement, a plurality of glove forms or mandrels 23. In the example shown there are 12 mandrels or glove forms on each strap. To insure that the straps 20 are firmly secured to the pallet each tubular member 11 has a pair of cams 24 mounted for pivotal movement on the respective end portions. Spring means 25 biases such cams 24 into engagement with the lower surface of the strap members and maintains such strap members 20 firmly secured to the pallet for movement therewith. The upper surface of the cams 24 are eccentrically contoured, as at 26, to insure a positive locking engagement with the respective straps 20.

The glove making apparatus comprises a suitable base or support means having vertically extending studs and cross braces, designated generally as 30 in FIG. 1a. Support means 30 has suitably mounted thereon guide means consisting of an upper guide section 31 and a lower guide section 32. Upper guide section 31 has a forwardly disposed pair of tracks that are generally C-shaped, designated 34 (FIG. 8), which extend along the upper respective side surfaces of the support means 30, such that the respective open portions face each other providing tracks for the movement of the respective side wheels 16 of the pallets, which arrangement is shown generally in FIGS. 8, 13 and 22. Located on the respective side edges in alignment with respective forwardly disposed tracks 34 are rearwardly disposed tracks 35 (FIGS. 1a and 1b) that are similarly C-shaped and are an extension of the tracks 34 forming a continuous path for the movement of the pallets described above. The lower section 32 of the guide means comprises pairs of aligned forwardly disposed tracks 36 and rearwardly disposed tracks 37 which, as shown in FIGS. 1a and 1b are in longitudinal alignment, and comprise pairs of C-shaped tracks which have the open portions facing each other as in tracks 34 and 35 to rollingly receive the wheels 16 of the pallets. A bridging section 33 of the guide means connects the respective forwardly disposed pairs of tracks 34 with the forwardly disposed tracks 36 of the lower section 32, wherein such bridging section 33 has curvilinear portions to facilitate movement of a pallet from the upper guide section 31 to the lower guide section 32. The rearwardly disposed pair of rails 35 of the upper guide sec-

tion 34 (FIG. 1b) has a receiving end 38 for a purpose to be described. An endless conveyor means 39 traverses a portion of the length of the forwardly disposed pair of tracks 34 and travels the full length of and parallel to the rails of rearwardly disposed tracks 35.

A transfer means, designated as 40, operates to convey pallets 10 from the endless conveyor 39 to an endless conveyor 41, which conveyor 41 has one end located on the forwardly disposed portion of tracks 34 of the upper guide section 31 and extends for the full length of the bridging section 33 for conveying pallets to the forwardly disposed tracks 36 of the lower guide section 32. Transfer means 40 has suitable vertically extending brackets 42 (FIG. 7) which support the forwardly disposed tracks 34 and a pair of spaced upper guideways 43. Suitable cross braces, as shown in FIG. 8, support a pneumatic cylinder 44 which has its piston rod 45 suitably connected to a bracket 46, which bracket 46 is connected to a carriage 47. Carriage 47 has a plurality of rollers 48 which are received by the guideways 43 to facilitate the reciprocation of carriage 47 thereon. Carriage 47 has a plurality of downwardly extending brackets 49 which have pneumatic cylinders 50 secured thereto. The respective rod ends of cylinders 50 have dogs 51 secured thereto which dogs have U-shaped recesses therein for frictionally engaging the axles 15 of the respective pallets for moving such pallets from the conveyor 39 to the conveyor 41 in a manner to be described.

Conveyor 41 has a plurality of sprockets 52 mounted on both sides of the supporting structure 30. However, only the one side is shown in FIGS. 1a, 1b, 2, 7 and 11. The respective sprockets 52 guide spaced drive chains, designated generally as 54 which ride on U-shaped guideways 55 (FIG. 11) that are substantially in side-by-side alignment and parallel to the guide rails of the bridging section 33. Certain links for the drive chains 54 have brackets 56 to which longitudinally spaced cross braces 57 are joined to thus assure alignment of chains. Extending perpendicularly outwardly from respective braces 57 are cam members 58 (FIG. 7) each with a U-shaped recess on its outermost end portion presenting a pair of leg members 59a and 59b. Leg member 59a is shorter than leg member 59b to facilitate engaging the axle 15 of the pallet 10 as it moves towards the sprockets 52, as is shown in FIG. 7. A dog 60, pivotally mounted on a bracket 29 adjacent to sprockets 52, prevents the accidental rearward displacement of the pallet 10 after it passes over such dog 60. The lowermost sprocket of the conveyor 41, designated as 53 in FIG. 2, is of a diameter such that the pallets 10 passing thereover are deflected at their pivots to an arcuate configuration. This disposes the respective outer end portions of the rows of glove forms away from each other to permit the stripping of the gloves therefrom, as shown in FIG. 2.

An indexing means, located on the lower forward portion of the support means (FIGS. 1a and 2), includes a pair of spaced motors 61 and 62. Motor 62 is connected by a pair of crank arms 63 and 64 to the intermediate portion 66 of a lever 65. Lever 65 has one end pivotally connected to a vertical support 67, of support means 30, and its other end connected to a truck 68, which truck 68 has spaced rollers 69 at the respective end portions thereof. In a similar manner a

plurality of other levers 65' (FIGS. 1a, b, and 3) are each pivotally connected to individual trucks 68. The trucks 68 are interconnected by rods 70 which assures simultaneous movement of the trucks 68 for a purpose to be described. Journaled for movement on the respective rollers 69 of each truck 68 is a U-shaped rail 71 (FIG. 10), which rail 71 has downwardly depending brackets 72 with each bracket having a recess 73 on its lower end. The recesses 73 are adapted to engage the axles 15 of pallets 10 to assure simultaneous movement of the respective pallets in a manner that will be described.

As viewed in FIGS. 1a and 2, the rearward end portion of rail 71 is pivotally secured to one end of a lever 75. The other end of lever 75 is pivotally secured to one end of crank arm 77. The other end of crank arm 77 is pivotally secured to a bearing block 78 which is mounted on a support channel 79. Crank arm 77 has its intermediate portion pivotally connected to one end of a pitman arm 80 which in turn is driven by the motor 61 through crank arm 81. Rotation of crank arm 81 operates to reciprocate the rail means 71 along a linear path, as viewed in FIGS. 2 and 3, which is first in a leftward direction and thence in a rightward direction.

Suitably mounted on the support means 30 are a plurality of L-shaped locking means 85. Each locking means 85 (FIGS. 12 and 13) has one arm member 86 extending upwardly and outwardly with a roller 87 journaled thereon in alignment with the rail 71 for rolling engagement therewith to thereby pivot the L-shaped member locking means 85 about pivot means 88, as seen in FIG. 12. The other arm member 89 of the locking means 85 has a recessed portion 90 which is adapted to engage the axle 15 of a pallet 10 to secure such pallet against linear movement. When the rail 71 is in a lowered position as shown in FIG. 12, it depresses roller 87, which in turn pivots the locking means 85 about pivot means 88 in a clockwise direction, as viewed in FIG. 12, thereby unlocking the pallet to permit the movement of the pallets in a manner to be described. A coil spring 91 is secured to the locking means 85 to bias such locking means in a counterclockwise direction as viewed in FIG. 12 which assures the locking of the pallet by the locking means 85 upon movement of rail 71 in an upward direction away from the locking means 85.

A transfer conveyor or elevator 100 is located on the rearwardmost portion of the glove making machine (as shown in FIGS. 1b, 5 and 6). Extending vertically are a pair of vertically spaced columns 101 with suitable guide rails 102 thereon. Elevator 100 has a pair of vertically extending channel members 103 connected by suitable cross braces 104. Bosses 105 secured to the respective side portions of channel member 103 have a central threaded bore therein and rollers 106 which frictionally engage the rails 102 to maintain the alignment. Each column 101 has a suitable boss 107 mounted on the lower portion thereon for supporting for rotation a threaded rod 108 which is threadedly received by a threaded bore of boss 105. The rotation of threaded rods 108 controls the vertical reciprocal movement of the channel members 103 and cross braces 104 on the guide rails 102. The upper end portion of each threaded rod 108 is connected to a right angle drive means 109 which in turn is connected via rod 110 to the output of variable speed motor 111.

Mounted on the upper cross brace 104 is a variable speed motor 115 whose output is connected by a shaft 116 with a pair of spaced right angle drives 117 to a pair of rods 118 which, in turn, are connected to right angle drives 119. The output of each right angle drive 119 is connected via an axle 120 to a track section 121. Hence, actuation of motor 115 rotates rods 118 and axle 120 which in turn rotate tracks 121. Each track 121 is C-shaped and in alignment with rearwardly disposed tracks 37.

The tracks 121 are located on both sides of the apparatus as shown in FIG. 6; however, only one side will be described. Each track 121 has an upwardly disposed longitudinally extending bracket 122 (FIGS. 14 through 18). The lower left end portion of the FIG. 6 depicts broadly the locking means which is shown more clearly in FIGS. 16, 17 and 18. Bracket 122 has a pair of bosses 125 which pivotally support an elongated bracket 126 as by a pair of levers 127 and 128. Bracket 126 has a plurality of downwardly extending projections 130 which are adapted to abuttingly engage the axles 15 of a pallet. Brackets 122 and 126, respectively, have laterally extending projections 131 and 132 in longitudinal alignment, as best seen in FIG. 16. One end of a rod 133 is secured to lateral projection 132, while the other end of rod 133 is slidably received by the lateral projection 131. A compression spring 135 encompasses rod 133 and operates between projections 131 and 132, such as to bias bracket 126 rightwardly as shown in FIG. 17 into locking position as shown in FIG. 18 whereby the projections 130 engage the respective axles 15. Pivotally secured as at 136 to an upwardly extending boss 137 (FIG. 16) of bracket 122 is a cam locking member 138. Cam locking member 138 has a semi-arcuately shaped recess 140 at its outermost end portion and an arcuately shaped recess 141 at its intermediate portion whereby recess 140 is adapted to frictionally engage and encompass a portion of axle 15 to secure and prevent the pallet from movement relative to bracket 122 while arcuately-shaped recess 141 facilitates the locking and unlocking in a manner to be described. A pin 142 is journaled on the outermost end portion of bracket 126 and rides in the arcuately shaped recess 141 to cam the locking member 138 upwardly out of engagement with the axle 15 as shown in FIG. 17 or into engagement with the axle 15 as shown in FIG. 18. As shown in FIGS. 17 and 18, mounted on tracks 37, closely adjacent to the transfer conveyor, is an unlocking means 150 comprising the bracket 151 which is secured to the guide rail having mounted thereon a cylinder 152 which has a piston 153 movably mounted therein with its rod 154 extending outwardly therefrom and in alignment with the pivotal bracket 126. Rod 154 is adjustably mounted on the piston rod to facilitate locking and unlocking of the cam member 138 with respect to the axle 15. Pressurization of the head end of cylinder 150 extends the rod 154 to engage bracket 126 which then moves bracket 126 leftward, as seen in FIG. 18, against the action of spring 135, whereby pin 142 moves, as by a pivoting action, the locking member 138 upwardly away from the axle 15 of the pallet. Conversely, upon pressurization of the rod end of cylinder 152, the reverse occurs with spring 135 returning the bracket 126 rightwardly so that pin 142 cams the locking member downwardly into locking engagement with the axle 15.

Located beneath the forward portion of guide rails 71 are a plurality of tanks A, B, C, D, E, and F. Tank A contains a suitable inlet pipe and drain to provide for supply of a liquid to the tank for a pre-wetting of the glove forms. Tank B is an ultra-sonic cleaning tank for suitably cleaning of the glove forms. Tank C is a rinse tank which may contain either cold or hot water. Tank D contains the hot rinse water while tank E contains the cold rinse water. Tank F contains a glove lubricant in liquid form, which on contacting the glove forms deposits a thin layer of lubricant thereon.

As shown in FIG. 3, tracks 36 are sectioned as at 36a and 36b to provide a sectioned track 36A. Track section 36A along with the pallets and glove forms thereon is adapted to be raised and lowered whereby the glove forms are dipped into the respective tanks A through E. A motor 160 (FIG. 4) mounted on suitable cross beams above tank C has its output connected via shafts 161 and 162 to right angle drive units 163 and 164 which in turn are connected respectively to rods 165, which in turn are connected to right angle drive units 166 for driving four downwardly extending threaded shafts 167. The respective tracks 36A (one on each side of the apparatus and only one side shown in FIG. 3) are connected to suitable brackets 170, which brackets 170 have threaded bosses which threadedly receive threaded shafts 167 to facilitate the raising and lowering of the tracks 36A and the pallets secured thereto for dipping the glove forms into the tanks. Suitable guide rollers 171 are mounted on brackets 170 for rolling engagement with guideways 172.

As shown in FIG. 1a, track 36 has another sectioned portion 36F adjacent to sectioned track 36A. Track section 36F is similar to track section 121 of that shown in FIGS. 5 and 6 in that track section 36F has connected thereto a motor similar to motor 111 which will raise and lower the track section 36F and in addition thereto has its track section 36F connected to a pair of right angle drives as 119 in FIG. 6 so that track section 36F can be rotated in arcs of revolutions for drying the glove forms mounted on pallets that are secured to such track sections. The pallets secured to track section 36F can thus be lowered, to dip the glove forms into the lubrication tank F located immediately below and thence be raised to remove the glove forms from tank F. Thereafter the pallets and track section 36F is rotated through a complete revolution and a half, such that the glove forms have the fingers pointing upwardly to dry the lubricant thereon and to assure an even distribution of the lubricant without permitting the collection of an excess amount of lubricant on the finger tips. With the glove forms resting in the fingers up position, the glove forms are conditioned for movement into the drying operation. The raising and lowering of the glove forms and pallet is similar to that shown in U.S. Pat. No. 3,320,638, the structure of which is incorporated herein by reference. A dry oven 180 is located adjacent to the tank F to receive the pallets 10 as they are conveyed from such tank F.

Located next in line after the dry oven 180 are tanks G, H and I. Tank G contains coagulation fluid such as calcium chloride in alcohol so that upon dipping of the form therein and thence withdrawing it from such tank, will leave a coating of coagulant on the glove forms. These forms are then dipped into the tank H which contains the latex compound and held in such tank H

for a period of time depending on the thickness of the layer desired. The coagulating action of the calcium chloride on the latex solution causes a smooth thin layer of coagulated rubber to be deposited on the surface of the form. The latex dipped glove forms are then dipped into tank I which contains carbon dioxide gas, which accelerates the coagulation of the latex on the glove form.

The section of the track 36 above tanks G, H and I are sectioned and indicated as 36G, 36H and 36I respectively. Each of these movable sections 36G, 36H and 36I are similar to the track section 36F and similar to elevator 100 wherein each track section is suitably supported by brackets such as brackets 122 which are movable upwardly and downwardly as by motor 111 as well as rotated as by motor 115 so that pallets located thereon dip the glove forms thereon into tanks G, H and I respectively and are then raised to clear the tanks and thence are revolved so that the pallets are moved through selected revolutions to assure an even distribution of the solutions as well as to facilitate the drying of such solutions on the glove forms and thereafter align track sections 36G, 36H and 36I with the tracks 36. The structure for raising and lowering such sectioned tracks is similar to that shown by U.S. Pat. No. 3,320,638 which structure is incorporated herein by reference. Suitable lock means identical to that shown in FIGS. 16, 17 and 18 are provided for track sections 36G, 36H and 36I to insure that the pallets 10 associated with each section of track and its pallets are manipulated as a unit. The individual track sections 36G, 36H, and 36I are individually manipulated so that each may be revolved in their own individual cycle.

The pallets on leaving the track section 36E are moved into a washer unit 185 via tracks 37 in cooperation with an endless conveyor 186. Washer unit 185 has suitable spraying heads therein supplied by water from a suitable pressure source for directing a spray onto the glove forms for a leaching operation. After the washing is completed the glove forms are moved closely adjacent the end of track section 37 (FIG. 5). This is accomplished by conveyor 186 leaving the pallet designated 10' in FIG. 5 such that a carriage 190 is adapted to transfer such pallet 10' into the position shown by pallet 10". Carriage 190 is secured to a pair of spaced racks 191 which racks are in meshing engagement with spur gears 192 adapted to be driven by suitable means not shown. Only one side of the carriage will be described. Carriage 190 has a pneumatic cylinder 193 which is adapted to raise and lower a U-shaped cam member 194. Cam member 194 is adapted to engage one of the axles 15 of the pallet located thereabove upon pressurization of the head end of cylinder 193. Once cam member 194 engages axle 15, such carriage 190 can transfer a pallet to and from the elevator as by rotation of the gear 192. After the transferring of a pallet is accomplished, it is secured to the elevator 100 by the locking means described above and as shown in FIGS. 16, 17 and 18.

Located immediately below elevator 100 is a dip tank J which contains a lubricant fluid which deposits a thin layer of lubricant on the glove forms in a manner to be described. It is to be noted that carriage 190 contains separate racks 191 on each side thereof to facilitate a smooth transfer of the pallet.

The elevator 100 positions the pallets for transfer to the endless conveyor 39 which operates to move the pallets with the forms thereon through the over 195. The pallets are transferred from the upper portion of the elevator 100 to the endless conveyor 39 by a carriage 190' that is similar in all respects to the previously described carriage 190. Carriage 190' is secured to a pair of racks 191', which racks 191' are in meshing engagement with spur gears 192' adapted to be driven by suitable means not shown. Carriage 190' has a pneumatic cylinder 193' which is adapted to raise and lower a U-shaped cam member 194'. Cam member 194' is adapted to engage one of the axles 15 of the pallet located thereabove upon pressurization of the head end of cylinder 193'. After engagement of axle 15 by cam 194', carriage 190' can transfer a pallet from the elevator as by rotation of gear 192'.

The latex tank H is a rectangular shaped vessel having end plates 200, a bottom plate 202 and side plates 201. A horizontally extending plate 203 lying closely adjacent to bottom plate 202 extends between and is secured to the respective side plates such as to provide a clearance space between plate 203 and end plate 201. A vertically extending plate member 205 is secured to plate 203 to separate the tank H in a pair of chambers 206 and 207. Support means 208 secured to the upper portion of tank H mounts a motor 210 and a bearing unit 211. A shaft 212 journaled in bearing unit 211 has a sheave 213 mounted on one end thereof and agitator blades 214 secured to the other end thereof. Plate 203 has an opening as at 215 to facilitate the flow of liquid downward through such opening 215. A plate 216 is keyed to shaft 212 closely adjacent to opening 215 to operate as a baffle. Motor 210 has its output connected via belt 219 to sheave 213 to provide power for rotating blades 214. Mounted on support means 208 is bracket means 217 which supports a filter screen supply roll 218. Bracket means 217 supports a motor 220 whose output is connected to a drive roller 221, which roller 221 is in rolling engagement with idler roller 222. A pair of closely adjacent rollers 225 and 226 are suitably mounted on bracket means 217 in line with roller 221 and supply roll 218.

A sleeve 228 is secured to the respective sides 201 of latex tank H adjacent to the upper ends thereof and closely adjacent to the abutment of plate 205 to sides 201. A U-shaped support rod 229 with depending legs 230 and 231 is supported by sleeves 228. Rod 229 supports a pair of downwardly extending brackets 232, which spaced brackets lie closely adjacent to the respective sides 201. Brackets 232 support a grid framework 233 to separate the filter cloth as it moves off supply roll 218 and into and thence out of the tank. An idler roller 237 is mounted on the lower portion of the spaced brackets 232 closely adjacent to the lower end portion of the grid frame 233. Idler rollers 234 and 235 are mounted between the upper end portions of brackets 232, such that rollers 234 and 235 are in line with roller 237. Supply roll 218 has a supply of filter screen material 238 rolled thereon and trained for movement over roller 226, thence over roller 235 and beneath roller 237 and thence over roller 234 for movement over idler roller 225 for movement between rollers 221 and 222 from which such filter material is directed downwardly into a suitable collector unit or onto a take up roll.

The temperature of the liquid in tank H is controlled by the circuit shown in FIG. 25, wherein coolant is refrigerated by a suitable chiller unit 240 for passage to a conduit 241. Conduit 241 conveys such coolant to the cooling coils 242 located in tank H via pump 243, conduit 244, pump 245 and heat exchanger 247. The coolant is thence conveyed from cooling coils 242 via conduit 248 to chiller unit 240 for cooling to a suitable temperature. A suitable temperature control monitor or temperature responsive means 249, having its probe located in tank H, controls valves 250A, 250B, 250C which in turn controls the flow of steam into a heat exchanger 247 which in turn determines the temperature of the coolant passing to coils 242. Under normal operating conditions the temperature control liquid passes from chiller unit 240 via conduit 241, through pumps 243 and 245, and into heat exchanger 247, thence to the coils 242 within tank H. At this time the valve 250A which controls the flow of steam into heat exchanger 247 is closed, so that no heat is imparted to the control liquid from heat exchanger 247. The cooling fluid from coil 242 is returned to the chiller 240 via conduit 248. This flow from chiller unit 240 to tank H and back to chiller unit 240 is indicated by solid arrow lines. Control monitor 249 continually monitors the temperature of tank H. Control monitor 249 upon sensing that the solution in tank H is below a preset minimum will send a signal to actuate control valves 250A, 250B and 250C. Actuation of valve 250A admits steam into heat exchanger 247 to heat the fluid flowing therethrough. Actuation of valves 250B and 250C blocks the flow of coolant from pump 243 and also blocks the return of coolant fluid to chiller unit 240 while simultaneously connecting the return flow of coolant from tank H via conduit 248 to valves 250C and thence to valve 250B to pump 245, where such fluid is pumped to heat exchanger 247 for subsequent flow to the coils 242 in tank H. This flow is indicated by the broken arrows in FIG. 25. Valves 250B and 250C act as by-pass valves so that the coolant fluid is continually circulated to the tank and steam is added to the heat exchanger unit only when required. In this instance, the trapped coolant fluid is recycled to the tank H and back through the heat exchanger until the tank temperature is within the preset limits and control monitor 249 re-sets valves 250A, 250B and 250C to direct the fluid flow as indicated by the solid line arrows in FIG. 25.

To simplify the coordination and understanding of the described stations reference is made to the timing chart as those skilled in the art may readily provide the suitable limit switches, interlocks, the electrical circuit and controls for effecting the coordination of the moving parts, therefore no such control elements have been herein illustrated. These controls are within the realm of erection by skilled mechanics and no invention is seen in using any of a variety of forms thereof which may be employed to accomplish the desired functions and the desired sequence as described herein.

In the operation of the apparatus described, it is assumed that a plurality of pallets with glove forms thereon are suitably located along the guide means 31, 33 and tracks 36, 37 and 35, spaced therealong for movement simultaneously to provide a continuous closed loop. References is also made to the timing chart which illustrates the coordination of the various steps.

The chart indicates a pallet has cleared the stripping operation and is ready to be picked up by the indexing unit. With the glove forms disposed in the position shown in FIG. 2, motor 62 is energized to rotate crank arms 63 in a clockwise direction which in turn moves crank arm 64 in a leftward direction, pivoting lever member 65, as well as the other lever members 65' downwardly. Such action causes trucks 68 (FIGS. 2 and 3) to move the rail means 71 downwardly so that the lower portion of the rail means engages the locking means 85 to pivot the lever arm members 86 in a clockwise direction, as seen in FIG. 12 and FIG. 2. Such position is indicated on the timing chart as occurring at two seconds. Pivoting of lever arm member 86 unlocks the pallets which is indicated on the timing chart to permit linear indexing movement thereof. Simultaneously with the downward movement of rail means 71, depending brackets 72 have their respective recesses 73 engaged with the axles 15 in preparation for an indexing movement. This position is shown in FIG. 1a and 1b wherein the respective lever members 65 and 65' are in a vertical downwardly extending position. Thereafter, motor 61 is energized, rotating crank arm 81 clockwise whereby rail means 71 is moved in a leftward direction indexing or advancing the respective pallets which are engaged by the brackets 72 in a leftward direction one position. This is shown on the timing chart as occurring between 5 and 8 seconds of time. Hence, the pallet that was located above tank A is moved to a position directly above tank B, the pallet located above tank B is moved to a position above tank C, and so forth. The end pallet, which was located above tank I, is moved into the entrance of washer unit 185 where it is subject to being picked up by the conveyor unit 186 for movement through the washing unit 185. Thereafter, motor 62 is energized such that it continues its clockwise motion whereby crank arm 63 moves the depending lever members 65 and 65' away from the vertical depending position to the position shown in FIG. 2 whereby rail means 71 is moved upwardly and away from the respective pallets such that the locking means 85 is released from its unlocked position and spring means 91 biases the arm member 89 with recess 90 to its locking position whereby recess 90 engages axles 15. Motor 61 is then energized to return the rail means to its rightwardmost position, as depicted by timing chart, in preparation for the following indexing action.

The pallets, that are then located above the respective tanks A through I, are moved downwardly with their section tracks 36A, 36F, 36G, 36H and 36I to dip the respective glove forms into their respective tanks. As previously described, the section track 36A moves its respective glove forms downwardly to dip the glove forms into tanks A through E respectively. Through the energization of motor 160 which rotates the respective shafts 167 through their right angled drive means 166 which in turn moves the brackets 72 simultaneously with section track 36A downwardly and thence upwardly out to remove the respective glove forms out of tanks A through E. The glove forms are pre-wet in tank A to condition the forms for cleaning. Thence the glove forms are cleaned in the ultrasonic cleaning tank B. The glove forms are then first rinsed in tank C and thence rinsed in hot water of tank D followed by cold

rinsing in tank E. With each indexing operation, the glove forms are advanced incrementally so that after the pre-wetting, the pallet and glove forms are indexed or advanced forward successively for these operations. 5 On completion of this operation the indexing means is again actuated as previously described to position the glove form that is located directly above tank E to the section track 36F wherein the pallet located thereon dips the glove forms thereon into tank F where the form receives a coating of lubrication. As indicated on the timing chart, lock means are actuated before the dipping so that upon completion of the dipping occurring after 20 seconds, the glove forms, pallet and track section 36F are raised for 8 seconds and thence rotated through one-half of a revolution (180°) such that the glove forms come to rest with the fingers pointing directly upwardly, in contrast to the downwardly depending glove forms from tanks A through E. During 10 the next indexing operation the pallets, which are located on track section 36F, are moved into the drying oven 180. The pallets and glove forms in oven 180 are moved therethrough by the successive indexing action described above. Thereafter, after several indexing operations the pallets are received by the section track 36G which operates to rotate the glove form and pallets into a downwardly depending position such that the fingers of the glove forms are pointed downwardly. 15 Thereafter the glove forms are dipped into a tank G containing a latex coagulation solution and thence withdrawn therefrom and manipulated through 180° to provide for an even dispersion of the coagulant fluid thereon. This is depicted by the 65 second unit on the chart, the dip being completed after 70 seconds and thence withdrawn up to the wrist by the 73rd second. The glove forms are fully withdrawn after 79 seconds, followed by rotation of the glove forms. In the next indexing operation the pallets with glove forms thereon are moved into track section 36H from which position the glove forms are dipped into latex tank H and withdrawn therefrom and thence rotated to provide an even dispersion of latex thereon. As previously noted all indexing is followed by an unlocking and then a locking, wherein the pallet is secured to the sectioned track as depicted by the timing chart. During the next indexing operation the pallets and glove forms thereon are indexed into track sections 36I from which position the glove forms are immersed into a carbon dioxide tank I which contains an atmosphere of gaseous carbon dioxide which hastens the coagulation of the latex on the glove forms. Upon withdrawal of the glove forms from tank I, the glove forms and pallets are revolved and thence positioned for movement into a washer unit 185. The glove forms and pallets are moved within washer unit 185 by an endless conveyor means 186 which positions such pallets after a period of time closely adjacent to the lower portion of elevator unit 100. 20 25 30 35 40 45 50 55 60 65

The pallet is moved from washer unit 185 by carriage 190. In the normal position carriage 190 is located immediately beneath the pallet designated 10' in FIG. 5 such that upon energization the pneumatic cylinder 193, cam member 194 moves upwardly to engage the axle 15 of pallet 10'. Gear 192 is then rotated to move rack 191 along with carriage 190 and pallet 10' outwardly into the position shown in the lower hand por-

tion of FIG. 5 whereby pallet 10' assumes the position of pallet 10''. Pneumatic cylinder 193 is then de-energized, whereby cam member 194 releases the pallet and gear 192 is rotated to return the carriage 190 rightwardly to a position whereby it is in a position to receive the next pallet with glove forms thereon. During such transfer action, locking means 150 is energized initially whereby rod 154 of piston 153 engages elongated bracket 126 such that the cam locking member 138 is pivoted into an upwardly extending position as shown in FIG. 17, whereby recess 140 is engaged with the axle 15 permitting movement of the pallet into position on carriage 190. Thereafter, a pneumatic cylinder 152 is de-energized, permitting spring 135 to bias bracket 126 into the position shown in FIG. 18, whereby recess 140 secures the axle 15 of the pallet thereon into a locked position which will permit rotation of the pallet and the glove forms thereon. Upon securing the pallet in position, motor 115 is energized to rotate the pallet 10 thereon into a position such that the glove forms thereon are in a downwardly extending position in preparation for the dipping operation. Thereafter, motor 111 is energized which rotates threaded rods 108 which lowers the pallet 10 downwardly, whereby the glove forms are dipped in lubrication tanks J which action deposits a thin layer of lubricant thereon. The glove forms are then withdrawn from tank J, then motor 115 is again energized which revolves the glove forms and the pallet 10 through a series of arcs to effect a drying operation and thereafter brought to a stationary position whereby the glove forms are in an upwardly extending position, as shown in FIG. 6. Thereafter, motor 111 is energized to rotate threaded rod 108 which then moves the pallets and the glove forms thereon upwardly to the position shown by the pallet 10 in phantom lines in the upper portion of FIG. 6 in preparation for transfer of such pallet to the drying oven 195. In a similar manner to carriage 190, carriage 190', the upper carriage, is moved outwardly through the rotation of gear 192' and thence brought rightwardly with the glove forms thereon to deposit such glove forms and pallet onto conveying means 39. The coordination of the transfer carriages 190 and 190' with elevator unit 100 is depicted by the timing chart. Such glove forms are moved slowly progressively through the drying oven 195 until they are deposited closely adjacent to the transfer unit 40. In the position shown in FIG. 7 carriage 47 is in a position whereby pressurization of the head end of pneumatic cylinder 50 extends dogs 51 downwardly such that it engages the axle of the pallet and upon pressurization of the rod end of cylinder 44 carriage 47 moves the pallet rightwardly to the next position. The rod end of cylinder 50 is then pressurized to disengage the dog 51 from the axle and the head end of pneumatic cylinder 44 is energized to extend the piston rod 45 and return the carriage 47 to the position shown in FIG. 7. Thereafter, pneumatic cylinders 50 are again energized whereby dog 51 is extended downwardly into engagement with one of the spaced axles 15 of the respective pallets such that the forwardly disposed pneumatic cylinder 50 is in a position to engage the previously indexed pallet such that the rearwardly disposed pneumatic cylinder 50 is in a position to engage the forwardly disposed axle 15 of the next pallet coming out of

the drying oven. Thus, with the pressurization of the rod end of pneumatic cylinder 44 a pair of pallets are moved rightwardly as shown in FIG. 7 whereby the forwardly disposed pallet is indexed onto the moving conveyor 41 while the pallet coming off of conveying means 39 is indexed into a position in preparation for movement onto conveyor 41. Conveying means 39 which operates on the pallets within the drying oven 195 as well as conveyor 186 which operates on the pallets within washer unit 185 are similar in construction in that an L-shaped bar 250 (FIG. 7 and FIG. 5) extends across spaced portion of the conveyor units such that they engage the pallet as the bar 251 comes up and around the end of the sprockets. The conveyor 41 has a plurality of spaced cam members 58 which are adapted to engage the axles of the pallets (note FIG. 8) and move the pallets along with the movement of the links of the conveyor. Conveyor 41 moves the pallets 10 with the glove forms thereon in a rightward direction as viewed in FIG. 1a and thence downwardly to the position shown in FIG. 2 whereby the channel members 11 of the articulated pallets are pivoted outwardly, separating the rows of glove forms which permits the stripping of the gloves from the glove forms. This action of pivoting the pallets on a small arc facilitates the spreading of the outer ends of the glove forms. The gloves which have been lubricated on the inside as well as the outside do not require inversion after the stripping operation and are in a condition for packing, thereby requiring less handling in the preparation for the shipping operation. Upon completion of the stripping operation, the pallets are deposited by conveyor 41 closely adjacent to the indexing means 35 whereby the forwardmost depending bracket 72 with recess 73 is in a position to engage the pallets 10 and index such pallets forwardly, or leftwardly, as viewed in FIG. 2, into a position such that they are immediately above tank A in preparation for the next complete automatic cycle. It is to be understood that each pallet is indexed progressively along the glove making apparatus such that each pallet with glove forms thereon goes through a sequence of operations until the forms reach the stripping operation, whereby the finished gloves are stripped and the forms then recycled through the apparatus. The coordination of the plural operations is depicted by the timing chart.

As depicted by such timing chart and with limit switches and interlocks between the component parts, there is assured a production of high quality products eliminating defective products. Interlocks and relay cooperate to assure coordination of the described motions and movement of the related parts. In addition interlocks are provided to assure the proper levels of solutions in the tanks within pre-set limits. These controls, interlocks and their circuits are obvious to one skilled in the art.

Various modifications are contemplated and may obviously be resorted to by those skilled in the art without departing from the described invention as only a preferred embodiment has been disclosed.

We claim:

1. An apparatus for forming articles comprising a plurality of article forms, a plurality of adjacent stations disposed in a closed path at least one of which stations is provided with an open top tank containing an

elastomer in liquid state in which the forms are vertically receivable; means to support a plurality of the forms for movement in aligned groups; means to move said groups of forms in alignment sequentially from one station to another in said closed path; means at the said one of said stations to sequentially move at least one group of forms vertically downwardly from alignment with the remainder of said groups of forms and back to alignment with the said remainder of the said groups of forms to thereby dip the forms of said one group into the liquid contained in the said tank; means to rotate said dipped forms in a group alternately in reverse directions in an arcuate path after withdrawal from the liquid; means to subject said dipped forms to an elevated temperature while transporting said forms in a direction at right angles to the direction of movement during dipping, whereby the elastomer on each of said forms is solidified into an article having the shape of the form; and means to effect relative arcuate movement between the forms in a group thereof to facilitate removal of the articles therefrom.

2. An apparatus as defined in claim 1 wherein the said means to support a plurality of glove forms in a group comprises a separate pallet for each group with each pallet including a plurality of parallel form supports; means hinging said supports for relative arcuate movement; and rollers on said pallets supporting the latter for translational movement.

3. The combination as defined in claim 2 wherein said means to move said groups of forms includes a horizontally reciprocating member mounted for movement above said forms; and means on said reciprocating member engageable with said pallets to move the latter when said member moves in one direction.

4. The combination as defined as claim 3 wherein the said member is mounted for vertical movement to and from pallet moving position; and the said means on said member comprises a plurality of horizontally spaced rigid arms extending vertically downward from said member and engageable with said pallets when said member is in pallet moving position.

5. An apparatus defined in claim 2 comprising a plurality of guide means for said rollers spaced in the direction of travel of said pallets; transfer means cooperative with said guide means to move the pallets between the guide means in the said closed path for said pallets; locking means mounted on said guide means operative to secure said pallets in fixed positions on said guide means; and moving means operative upon actuation to release said pallets from said locking means and move said pallets on said guide means.

6. An apparatus as set forth in claim 5 wherein said moving means includes index means; said index means including elongated rail means mounted for movement between a first position and a second position; said rail means in said first position being out of contact with said locking means; pallet engaging means on said rail means; said rail means in said second position operative to actuate said locking means to pallet releasing position and dispose said pallet engaging means in contact with the latter.

7. An apparatus as set forth in claim 6 wherein said locking means includes a lever pivotally mounted between its ends with one outer end portion in alignment with said rail means and the other outer end por-

tion of said lever being selectively operable to engage said pallet for securing said pallet in locked position on said guide means.

8. An apparatus as set forth in claim 6 wherein the 5 mounting for said rail means includes a plurality of interconnected pivot means supporting said rail means at a plurality of spaced locations; said pivot means including means journaling said rail for reciprocal movement in a direction parallel to said guide means; first drive means connected to said pivot means for moving said pivot means between a first and a second position; and second drive means connected to said rail means for reciprocating said rail and said pallets in contact with said pallet-engaging means.

9. An apparatus for forming articles by dip coating a 10 plurality of forms comprising, a support frame, guide means mounted on said support frame, a plurality of open top liquid containing tanks beneath said guide means, a plurality of pallets supported on said guide means for movement thereon, each of said pallets having a plurality of article forms thereon, locking means on said guide means normally operative to secure said pallets in selected fixed positions on said guide means, 15 portions of said guide means over said tanks being sectioned and movably supported to permit movement of said portions relative to said frame, each of said movable portions having at least one of said locking means, first drive means connected to one of said movable portions for reciprocating the latter and pallets locked thereon between an upper position and a lower position to effect the dipping of said forms into and removal out of tanks, said one portion in said upper position being 20 in alignment with the remainder of said guide means to receive pallets therefrom and transfer pallets thereto, other drive means connected to certain other portions of said guide means for reciprocating said other portions between an upper position and a lower position, 25 at least one of said other portions of the guide means being supported for rotation thereof and of said pallets secured thereto about a central axis to thereby effect an even distribution of liquid material on said forms, 30 and index means operative to release said pallets from said locking means and thereafter move all of said pallets on said guide means.

10. An apparatus as set forth in claim 9 wherein said 35 guide means comprise spaced parallel guide rail means, each of said pallets has axles supporting guide wheels for rotation within said guide rail means, and said locking means comprises lever means normally biased into locking engagement with said pallets.

11. An apparatus as set forth in claim 10 wherein 40 said index means comprises an elongated rail means, a plurality of pivoted rods supported by said support frame and pivotally supporting said rail means for movement relative to and parallel to said guide rail means, drive means interconnected to said pivoted rods to provide simultaneous movement of said rods to lower and raise said rail means toward and away from said guide rail means, a plurality of downwardly extending brackets secured to said rail means and longitudinally spaced thereon, each of said brackets having a U-shaped recess on its lower end portion for receiving one of said axles of said pallets upon movement of said rail means toward said guide rail means.

12. An apparatus as set forth in claim 11 wherein said locking means comprises a plurality of L-shaped lever means, each of said L-shaped lever means having a pair of leg members, one leg member of said lever means having a recess on the end thereof for normally receiving one of said axles of said pallets to prevent movement thereof, the other leg member of said lever means extending upwardly in alignment with said rail means for engagement thereby when said rail means is moved toward said guide rail means to pivot said one leg member away from axles of said pallets to permit linear movement of said pallets.

13. An apparatus as set forth in claim 12 wherein motive means are operatively connected to said rail means for selectively reciprocating said rail means in a direction parallel to said guide rail means to advance said pallets linearly simultaneously on said guide rail means.

14. An apparatus for automatic manufacture of gloves from latex comprising: a plurality of glove forms; means to clean said forms comprising a plurality of tanks containing cleaning liquid and means to dip said forms sequentially in each of said tanks when the forms are in alignment therewith; means to apply a lubricant slurry to said forms; means to dry said lubricant slurry on said forms; means to dip said lubricant covered forms fingers first a predetermined depth into a liquid coagulant medium of latex; means to dip said coagulant coated forms fingers first into a body of latex, withdraw said forms from the latex and rock them in an arcuate path; means to subject said latex dipped forms to an atmosphere of carbon dioxide; means to thereafter subject said latex coated forms to a liquid spray; means to dip said sprayed latex coated forms in a lubricant slurry; means to subject said lubricant dipped latex coated forms to a drying and curing temperature; a glove stripping station spaced from said drying and curing means, and conveyor means to move said forms sequentially to each of said dipping, drying, and curing means in the order named, thereafter to the said glove stripping station and thence back to the first-named means in a closed cycle.

15. An apparatus for dip coating a plurality of forms to form articles thereon, comprising: support means; guide means mounted on said support means; said guide means having upper, lower and bridging sections; said upper section having a receiving end; said lower section having a discharge end; a first transfer means operative between said discharge end and said receiving end to define a closed continuous flow path with said guide means; said lower portion having forwardly and rearwardly disposed continuous linear tracks; said upper portion having forwardly and rearwardly disposed continuous tracks; said bridging section joining said forwardly disposed tracks of said upper portion with said forwardly disposed tracks of said lower portion; a plurality of pallets mounted on said guide means for movement thereon; each of said pallets being articulated; each of said pallets having a plurality of mandrels thereon; first conveyor means having a conveying run operative over the full length of said rearwardly disposed track of said lower portion; second conveying means having a conveying run operative over the full length of said rearwardly disposed track of said upper run; third conveyor means having a conveying means

operative over the full length of said bridge portions and over a portion of the forwardly disposed tracks of said upper portion of said guide means; second transfer means cooperative with said guide means and operative to transfer pallets from said second conveyor means to said third conveyor means; index means operative over the full length of said forwardly disposed tracks of said lower portion of said guide means to transfer pallets from said bridging portion of said guide means and forwardly along said forwardly disposed tracks of said lower portion of said guide means and onto said first conveyor means; and said bridging portion having a curvilinear portion that is operative to open up said articulated pallet to accentuate the distance between the outermost end portions of said mandrels located thereon.

16. An apparatus for dip coating a plurality of glove mandrels as set forth in claim 15 wherein locking means are mounted on said guide means; said locking means being normally operative to secure said pallets in fixed positions on said guide means; said forwardly disposed tracks are sectioned to permit relative movement of the tracks relative to the support; first drive means connected to certain ones of said sectioned tracks for reciprocating said one sectioned tracks and the pallets thereon for movement between an upper position and a lower position; cleaning tanks positioned below and in alignment with said certain ones of said sectioned tracks to clean the mandrels located on said pallets secured thereto; motive means connected to another one of said sectioned tracks for reciprocating said other sectioned track and the pallets thereon between an upper position and a lower position and to rotate said other sectioned track about an axis that is normal to said tracks; a lubrication tank located below and in alignment with said other sectioned track to provide lubrication onto said glove mandrel as said other sectioned track and said pallet thereon moves into said lower position; a washing station encompassing said rearwardly disposed tracks of said lower portion of said guide means; a drying oven encompassing the intermediate portion of said forwardly disposed tracks of said lower guide means; a latex dip tank and a coagulant dip tank located beneath said guide means and between said washing station and said drying oven; said lower portion of said guide means having a pair of sectioned tracks located above said latex dip tank and said coagulant tank respectively; power operated means connected to said pair of sectioned tracks for reciprocating said tracks and pallets located thereon into and out of said dip tank and said coagulant tank and for rotating said pair of sectioned tracks with said pallets thereon through arcs of revolution; and a heating oven encompassing said rearwardly disposed tracks to cure gloves on said mandrels on said pallets passing therethrough.

17. An apparatus for dip coating a plurality of mandrels to form articles thereon as set forth in claim 16 wherein a lubrication tank is located beneath said first transfer means, said first transfer having a carriage that is operative to rotate and reciprocate a pallet held thereby to dip mandrels thereon into and out of said last-mentioned lubrication tank.

18. An apparatus for dip coating a plurality of mandrels to form articles thereon as set forth in claim 17

wherein a carbon dioxide tank is located between said latex dip tank and said washing station, and said guide means above said carbon dioxide tank being sectioned for vertical reciprocal movement; means connected to said last-mentioned sectioned guide means above said carbon dioxide tank for reciprocating and rotating said last-mentioned sectioned guide means and pallets with mandrels thereon into and out of a carbon dioxide tank for conditioning the delivery of said last-mentioned pallets to said washing station.

19. An apparatus for dip coating a plurality of forms as set forth in claim 15 wherein each of said pallets has a plurality of elongated members, pivot means connecting adjacent members together to provide articulation between said members, each of said members having a strap mounted thereon, spring biased cam means on each member for releasably securing said straps to said

members, and each strap having a plurality of forms secured thereto.

20. An apparatus for dip coating as set forth in claim 19 wherein each of said elongated members has side brackets, said pivot means includes axles pivotally joining adjacent ones of said brackets, rollers mounted on said axles for guiding said pallet along guideways to facilitate movement thereon and articulation thereof to facilitate the stripping of articles from said forms.

21. An apparatus for dip coating as set forth in claim 19 wherein each of said members has stop means thereon midway between the respective ends thereof for locating said straps thereon, and said stop means includes a spring clip operative to secure said straps on said members.
